Patented Aug. 22, 1911.

Fig. 1.

UNITED STATES PATENT OFFICE.

ANGUS MCKENZIE, OF CANTON, OHIO, ASSIGNEE OF ONE-HALF TO WILLIAM H. MELDON,
OF JAMAICA, NEW YORK.

AERIAL PROPELLER.

1,001,291.

Specification of Letters Patent. Patented Aug. 22, 1911.

Application filed April 21, 1910. Serial No. 556,686.

To all whom it may concern:

Be it known that I, ANGUS MCKENZIE, a citizen of the Dominion of Canada, and resident of Canton, in the county of Stark and State of Ohio, have invented certain new and useful Improvements in Aerial Propellers, of which the following is a specification.

This invention relates to aerial propellers and the primary object thereof is to provide a propeller of such class which can be used either as a driving or a driven medium.

A further object of the invention is to provide a propeller of such class in a manner as hereinafter set forth whereby by its construction and arrangement it will give the greatest possible power with the least weight.

A further object of the invention is to provide in the supporting frame for the mounting of the blades or sails whereby an efficient operation of the propeller is attained.

Further objects of the invention are to provide an aerial propeller in the manner as hereinafter set forth and which is simple in its construction and arrangement, strong, durable, efficient in its use, conveniently set up, capable for use for driving or driven purposes, comparatively light in weight and inexpensive to manufacture.

With the foregoing and other objects in view, the invention consists of the novel construction, combination and arrangement of parts, as hereinafter more specifically described and illustrated in the accompanying drawings, wherein are illustrated the preferred embodiments of the invention, but it is to be understood that changes, variations and modifications can be resorted to which come within the scope of the claims hereunto appended.

In the drawings:—Figure 1 is a perspective view of one form of an aerial propeller in accordance with this invention, Fig. 2 is a like view of a modification, Fig. 3 is a side elevation of the form shown in Fig. 1, the stay rods being omitted, and Fig. 4 is an elevation of a blade or sail before the mounting thereof.

Preferably four blades or sails are used when setting up the propeller, but the number of the blades or sails may be varied for special purposes and under certain conditions. In Figs. 1, 2 and 3, the blades or sails

are shown in the position which they assume when in action or in the operative position.

Each of the blades or sails is substantially in the form of a mixtilinear triangle and referring to Fig. 4, the blade or sail is indicated by the reference character 1 and has a straight edge 2 and another of its edges extending for a short distance at right angles with respect to the terminus 2^a of the edge 2, as at 3 and the remaining portion 65 of the edge upon the arc of a circle, as at 3^a and which merges into the terminus 3^b of the edge 4, the latter being curved and having its other terminus merging in the terminus 2^b of the edge 2. In Fig. 4 the dotted 70 line 4^a indicates the hypotenuse to show the extra amount of area for the blade or sail obtained by curving the edge 4 in connection with the curved edge portion 3^a. The blades or sails are formed from thin canvas or 75 thick oiled silk having sufficient body so that the blades or sails will not only be flexible but unusually strong. Although it is preferable to use canvas or thick oiled silk, yet any suitable material that would answer for 80 the purpose may be employed. The blades or sails may be reinforced by the usual seams or may be corded or thickened by a double weaving, as indicated by the double dotted lines 4^b in Fig. 4.

The frame work illustrated in Fig. 1 and to which the blades or sails are mounted or connected includes a shaft 5 having fixed thereto a four-way coupling 5^a and also has attached thereto a power transmission, as 90 shown by way of example a sprocket 12.

To each of the branches of the four-way coupling 5^a is secured an arm 6. The arms 6 are radially disposed with respect to the axis of the shaft 5 and to each arm is attached a blade or sail 1. The arms 6 are braced through the medium of a pair of diamond shaped stay frames, one overlapping the other and one extending in an opposite direction with respect to the other.

One of said stay frames is formed from a series of stay rods 7 and the other from a series of stay rods 8. The stay rods 7 at their outer ends are connected to the outer ends of a pair of arms 6 and at their inner ends are connected by the coupling member 7^a to the other pair of arms 6 intermediate the ends of these latter. The stay rods 8 at their outer ends are connected to the outer end of a pair of arms 6 and at their 105 110

inner ends are connected by the coupling members 8^a to the other pair of arms 6 intermediate the ends of these latter.

The frame work as illustrated in Fig. 2 includes a shaft 15 having attached thereto a pair of four-way couplings 16, 17 and also has connected thereto a power transmission means, by way of example, a sprocket 12^a. Connected to each of the branches of the couplings 16 is an arm 6^a and attached to each of the branches of the couplings 17 is an arm 10. The arms 6^a are arranged in parallelism with respect to the arms 10 and the said arms 6^a and 10 are radially disposed with respect to the axis of the shaft 15. Each set of arms 6^a and 10 is braced through the medium of a pair of diamond shaped frames, the stay frame of each pair overlapping each other and extending in an opposite direction with respect to each other. One of said stay frames for the set of arms 6^a is formed from a series of stay rods 7^b and the other from a series of stay rods 8^b. The stay rods 7^b at their outer ends are connected to the outer ends of a pair of arms 6^a and at their inner ends are connected by the coupling members 7^a to the other pair of arms 6^a intermediate the ends of these latter. The stay rods 8^b at their outer ends are connected to the outer ends of a pair of arms 6^a and at their inner ends are connected by the coupling members 7^a to the outer pair of rods 6^c intermediate the ends of these latter. One of said stay frames for the set of arms 10 is formed from a series of stay rods 7^c and the other frame from a series of stay rods 8^c. The stay rods 7^c at their outer ends are connected to the outer ends of a pair of arms 10 and at their inner ends are connected by the coupling members 7^a to the other pair of arms 10 intermediate the ends of these latter. The stay rods 8^c at their outer ends are connected to the outer ends of a pair of arms 10 and at their inner ends are connected by the coupling member 7^a to the other pair of arms 10 intermediate the ends of these latter. The ends of the arms 6^a are connected to the ends of the arms 10 by longitudinally-extending rods 11.

50 When the propeller is set up in the manner as shown in Fig. 1, the straight edges of the blades or sails are arranged against the shaft 5. When the propeller is set up in the manner as shown in Fig. 2 the straight edges of the blades or sails are arranged against the rods 11.

60 The shafting is constructed of any suitable light metal in the form of tubing and the other elements of each of the frames are sufficiently thick to withstand the torsion and strain of the blades or sails. The blades or sails are fastened to the shaft, arms and rods by lacing or in any other suitable manner.

66 The foregoing being the construction, the

operation of the propeller is as follows:— When used as a driven propeller, as on airships, iceboats, or for forcing any vessel ahead either in a gale or calm or between these two extreme points any driving means 70 may be used to give rotary motion to the journaled shaft, in the direction shown by arrows, the wide end of the sails facing the direction of travel. The air fills the sails which assume a shape somewhat like a bird's 75 wing in flying, forming a pocket at or near the radial arms, as shown at A in Figs. 1 2 and 3, whereby the vessel is forced forward, the air sliding along the sails until it is freed as it nears the points. Each sail 80 engages the air immediately in front as it advances consequently in striking the air, the greatest resistance is at the wide part of the sail where it is secured to the radial arms. 85

If the propeller is to be used as a driver, as in the case of windmills, the general construction is as described but in operation the action is reversed. That is to say, the shaft is mounted in journals as stated, but the sails 90 are pointed in a reverse direction with the points toward the wind. When the wind strikes the sails it causes them to fill and assume the shapes shown in Figs. 1, 2 and 3, the wind pressure at the points, owing to 95 the area being much less there than at the wide parts where fastened to the radial arms and where the greatest resistance is had. The propeller when used as a driving means revolves in the opposite direction shown by 100 the arrows.

From the foregoing description taken in connection with the accompanying drawing, the advantages of the construction and of the method of operation will be readily apparent to those skilled in the art to which the invention appertains and I have described the principle of operation of the invention together with the device which I now consider to be the best embodiment 110 thereof.

What I claim is:—

1. An aerial propeller comprising a rotatable element, a plurality of radially-disposed arms connected therewith, a flexible blade attached to each of said arms and to said element and provided with a straight edge and a pair of curved edges, one of said curved edges intersecting the other and said curved edges intersecting said straight edge, 115 and a pair of stay frames connected to and bracing said arms.

2. An aerial propeller comprising a rotatable element, a plurality of radially-disposed arms connected therewith, a flexible blade attached to each of said arms and to said element and provided with a straight edge and a pair of curved edges, one of said curved edges intersecting the other and said curved edges intersecting said straight edge, 125 130

- and a pair of stay frames connected to and bracing said arms, said stay frames overlapping and extending in opposite directions with respect to each other.
5. 3. An aerial propeller comprising a longitudinally extending rotatable element, a plurality of radially-disposed arms connected therewith, and flexible blades, each substantially in the form of a mixtilinear triangle and connected with an arm of said element, the straight edge of said blade disposed parallel with said element.
10. 4. An aerial propeller comprising a longitudinally extending rotatable element, a plurality of radially-disposed arms connected therewith, and flexible blades, each substantially in the form of a mixtilinear triangle and connected with an arm and said element, the straight edge of said blade disposed parallel with said element, and means engaging with said arms for bracing them.
15. 5. An aerial propeller comprising a longitudinally extending rotatable element, a plurality of radially-disposed arms connected therewith, and flexible blades, each substantially in the form of a mixtilinear triangle and connected with an arm and said element, the straight edge of said blade disposed parallel with said element, and a pair of stay frames connected to said arms for 30 bracing them, said stay frames overlapping and extending in opposite directions with respect to each other.
20. 6. An aerial propeller comprising a longitudinally extending rotatable element, a plurality of radially-disposed arms connected therewith, and flexible blades, each substantially in the form of a mixtilinear triangle and connected with an arm and said element, the straight edge of said blade disposed parallel with said element, and a pair of stay frames connected to said arms for 35 bracing them, said stay frames overlapping and extending in opposite directions with respect to each other.
25. 7. An aerial propeller comprising a longitudinally extending rotatable element, a plurality of radially-disposed arms connected therewith, and flexible blades, each

substantially in the form of a mixtilinear triangle, and connected with an arm and said element, the straight edge of said blade disposed parallel with said element, and a pair of stay frames connected to said arms 30 for bracing them.

8. An aerial propeller comprising a longitudinally extending rotatable element, a plurality of radially-disposed arms connected therewith, and flexible blades, each 35 substantially in the form of a mixtilinear triangle and connected with an arm and said element, the straight edge of said blade disposed parallel with said element, and a pair of stay frames connected to said arms for 40 bracing them, said stay frames overlapping and extending in opposite directions with respect to each other.

Signed at Canton in the county of Stark and State of Ohio this 14th day of April 45
A. D. 1910.
